Patented Oct. 26, 1920.

UNITED STATES PATENT OFFICE.

HENRY C. BARGER, OF NEW YORK, N. Y.

TOY.

1,356,901.

Specification of Letters Patent.

Patented Oct. 26, 1920.

Application filed March 20, 1920. Serial No. 367,399.

To all whom it may concern:

Be it known that I, HENRY C. BARGER, a citizen of the United States, and resident of New York city, in the county of Queens and State of New York, have invented certain new and useful Improvements in Toys, of which the following is a specification.

My invention relates to improvements in the class of toys comprising a vehicle and the figure of an animal thereon, the object of my invention being to cause movement of the head and one or more members thereof, such as the arms, when the vehicle is moved along a support.

In the specific example of my invention illustrated in the accompanying drawings, I provide a vehicle having wheels, a body on the vehicle having a pivoted head and pivoted arms and a slide member guided within the body to be moved by one of the wheels, said head being tilted by said member when the latter moves in one direction, and the arms being operatively connected with said members to be rocked when said member reciprocates.

My invention also comprises novel details of improvement and combinations of parts that will be more fully hereinafter set forth and then pointed out in the claims.

Reference is had to the accompanying drawings forming part hereof wherein—

Figure 1 is a side elevation of my improved toy, partly in section and part of the garment of the body being broken away;

Fig. 2 is a vertical section on the line 2, 2 in Fig. 1, and

Fig. 3 is a sectional detail.

The numeral 1 indicates a vehicle, shown resembling a sled, having a base board 2 from which depends spaced side walls 3 between which wheels 4, 5 are pivoted. The rear wheels 5 are shown spaced apart and provided with pivots 6 carried by walls 2, a crank-pin 7 being secured to wheels 5 in an eccentric position therebetween. Upon base 1 are sides 8 and a back board 9 to resemble the seat portion of a sled.

A toy body or figure is indicated at 10 seated upon base 3 between the sides 8 and back 9 to which the body may be attached by screws. The body or figure may be of an animal, a particular feature being to represent it in the characteristic of Santa Claus, the coat being shown at 11. Said body may be made of wood or other suitable material, the same being shown provided with a trunk

portion 12, a head 13 the neck portion 13^a of which is pivoted forwardly at 14 to the trunk, at one side of the vertical center of the head, and arms 15, 16. The arm 15 is shown pivoted to the trunk 12 at 17 to extend forwardly, and the arm 16 is shown pivoted to the trunk at 18 to extend outwardly laterally of the body. The interior of the body is provided with a vertical guideway 12^a which opens through base 2 and 2^a and reciprocative within said guideway is a slide member 19 provided with a depending extension 20 passing freely through opening 2^a and provided with a curved lower face 20^a over and co-operative with crank-pin 7. The extension 20 is shown pivotally connected to member 19 to swing as required when engaged by crank-pin 7. The upper end of member 19 opposes the neck portion of head 13, and since the latter is pivoted forwardly at 14 the tendency of the head will be to tilt backwardly. The neck is shown provided with side lugs 13^b, to oppose slide member 19 and with a rearward projection 13^c over a shoulder or stop 13^b, on the trunk 12. The arm 15 is provided with a pin or projection 21 operative in an opening 22 in the trunk of body 10 and shown entering a hole 23 in slide member 19, whereby as the latter is reciprocated the arm 15 will be rocked. The inner pivotal portion of arm 16 rocks in an opening 24 in the trunk of body 10 and the inner end of said arm is located in an opening 25 in slide member 19, whereby as the latter is reciprocated the arm 16 will rock.

When the toy vehicle is moved along the floor its wheels will revolve and the crank pin 7, operating against the base 20^a, will raise the slide member 19, which will push on the lugs 13^b of neck 13^a and cause the head 13 to tilt forwardly, the slide member 19 at the same time raising projection 25 and the inner end of arm 16, thereby causing said arms to rock downwardly, as indicated by the dotted positions of the head and arms in Figs. 1 and 2. When the crank pin descends from the high position the slide member will descend (by gravity) thus releasing the head and permitting the same to tilt backwardly, the descent of the slide member causing the arms 15, 16 to rock upwardly. The continued rotation of crank-pin 7 will cause rocking of the head and arms while the toy is propelled forwardly or backwardly. Since the surface 20^a is

curved over crank-pin 7 the latter can operate member 19 in either direction of rotation of the crank-pin.

My improved toy is simple in construction and cheap to manufacture, requiring no gears or springs for operation of the parts, and will be pleasing and amusing for children. The toy may be made almost entirely of wood so as not to injure the children playing with it. If preferred, only one of the arms need be connected to member 19 for rocking it.

Having thus described my invention, what I claim and desire to secure by Letters 15 Patent is:—

1. A toy comprising a vehicle having wheels, a body mounted thereon, a head pivotally supported at the forward side of its vertical center to tilt rearwardly relatively 20 to the body, a slide member mounted within the body independent of the head in position to engage and tilt the head when moving in one direction, the head being adapted to automatically return when the member 25 moves reversely, and means to actuate said member by one of the wheels.

2. A toy comprising a vehicle having wheels, a body mounted thereon, a head pivotally supported on the body to tilt, an arm 30 pivotally carried by the body, a slide member mounted within the body separate from the head in position to engage and tilt the head when moving in one direction and operatively connected with the arm to rock 35 the same, and a crank-pin connected with one of said wheels to actuate said slide member.

3. A toy comprising a vehicle having wheels, a body mounted thereon and provided with a head pivotally supported on the body to tilt, an arm pivotally carried by the body, a slide member mounted within the body separate from the head in position to engage the head at one side of its 45 pivot to tilt the head and operatively connected with the arm to rock the same, and a crank-pin connected with one of said wheels, said slide member having a pivoted extension provided with a curved surface over the crank-pin to be engaged by the latter to actuate the slide member.

4. A toy comprising a vehicle having wheels, a body mounted thereon and provided with a head and an arm pivotally 55 carried by the body, a slide member mounted within the body in position to engage and tilt the head, said slide member having an opening, the inner end of said arm being

located in said opening for operation of the arm, and means to actuate said member by one of said wheels.

5. A toy comprising a vehicle having wheels, a body mounted thereon and provided with a head, said head being pivoted on the body at one side of the vertical center 65 of the head, an arm pivotally carried by the body, said body having a vertical guideway below the head, a slide member in said guideway independent of the head in position to engage and tilt the head, said arm being operatively connected with said slide member to rock the arm, and means to actuate said member by one of said wheels.

6. A toy comprising a vehicle having wheels, a body mounted thereon and provided with a head, said head being pivoted on the body at one side of the vertical center of the head, an arm pivotally carried by the body, said body having a vertical guideway below the head, a slide member in said 70 guideway in position to engage and tilt the head, said arm being operatively connected with said slide member to rock the same, and a crank-pin connected with one of said wheels to actuate the slide member.

7. A toy comprising a vehicle having wheels, a body mounted thereon and provided with a head and an arm, said head being pivoted on the body at one side of the vertical center of the head, said arm being pivotally carried by the body, said body having a vertical guideway below the head, a slide member in said guideway in position to engage the head at one side of the head to tilt the head, said arm being operatively connected with said slide member to rock the arm, and a crank pin connected with one of said wheels, said slide member being provided with a curved surface over said crank-pin to be engaged thereby to 100 actuate said member.

8. A toy comprising a vehicle having wheels, a body mounted thereon and provided with a head and an arm pivotally carried by the body, a slide member mounted within the body in position to engage and tilt the head and operatively connected with the arm to rock the same, said member having a depending extension pivotally connected therewith, and a crank-pin connected 105 with one of said wheels to operate said extension and slide.

Signed at New York in the county of New York and State of New York this 19th day of March, A. D. 1920.

HENRY C. BARGER.
